ABSTRACT OF THE DISCLOSURE

A high energy rate forming machine having a ram actuated by a piston which has one of its ends in a gas pressure chamber, the inner end of the piston being equipped with a plunger tightly receivable in a cylinder which is connected via a check valve to the interior of the chamber, the vacuum formed in said cylinder when said plunger is thrust therewith holding the piston until a switching valve connects said chamber to said cylinder. Hydraulic jack means entirely outside the chamber is used to raise the descended piston so that the plunger re-enters the cylinder to lock the piston in its upward position. The hydraulic jack may also be used to trigger the release of the piston by forcibly withdrawing the plunger from the cylinder.

Background of the invention

The present invention relates to a high energy rate forming machine in which a ram is actuated at a high rate by the action of a gaseous pressure and thus actuated ram acts on various materials, especially metals, with a high energy rate forming force.

It has been found that when a material or work is plastically deformed, if the plastic deformation operation is effected at a great rate the material is deformed with a high impact force, and accordingly, the plastic deformation rate of the material by the utilization of such an impact force is quite higher than when the same material is plastically deformed at an ordinary or slower rate. Therefore, it can be assumed that when the same principle is utilized in the plastic deformation of a metallic material the deformation operation would be carried out with a quite high efficiency. In a press type machine which is a typical machine in which the above principle is utilized one metal mould is supported by a stationary platform and the other metal mould is secured to a ram which is actuated at a high rate whereby when the ram is actuated a material or work is imparted a desired plastic deformation thereto by a cooperative action between the two moulds.

In such a press type machine, gas is outwardly discharged at the upper dead point of the ram stroke whereby by the force which pushes down the ram is overcome by the force which pushes up the ram so that the ram may maintain its initial position. However, such a type machine has a drawback that a large amount of gas is outwardly discharged resulting in loss of a great amount of gas. In order to remedy the drawback there has been proposed that gaseous pressure is caused to act on the upper surface of the ram and oil pressure is caused to act on the lower surface of the ram thereby to maintain the ram at its predetermined initial position, but this increases the resistance by a great extent and the ram can not be actuated at a high rate. Furthermore, since the ram initiates its proper impact stroke directly from its initial or non-operative position, if the ram has not been so designed that it may maintain its initial operation without fail the operator may be exposed to possible hazards.

2

Summary of the invention

Therefore, the main object of the present invention is to provide a high energy rate forming machine in which the ram is actuated by means of gas pressure and the initial position of the ram is maintained by the same gas pressure.

Another object of the present invention is to provide high energy rate forming machine in which when the ram is actuated by gas pressure, initially the ram slowly moves along a preliminary stroke passage and thereafter initiates its proper impact stroke.

According to the present invention, the ram is provided with a piston and the piston is adapted to be moved into a gas pressure chamber which has a substantially large diameter than that of the piston and seals gas under high pressure therein. The ram piston is actuated at high rate by the gas pressure of the gas pressure chamber which acts on one end surface of the piston whereby high rate energy is generated by the actuation of the piston and such energy is utilized for plastic formation of work. In order to permit the ram piston to move along a suitable distance of preliminary stroke before it initiates the proper plastic formation stroke, a mechanism which comprises a combination of a plunger and a cylinder is provided between the adjacent end of the piston and the above gas pressure chamber, the cylinder has a size just sufficient to receive the plunger. When the plunger has entered into the cylinder, the gas pressure within the gas pressure chamber does not act on the end surface of the piston, and accordingly, the ram piston is not imparted driving force thereto, but when the ram piston is desired to be actuated the plunger is caused to come out of the cylinder and at the same time the pressure within the gas pressure chamber actuates the ram piston. In other words, the movement of the plunger from within the cylinder to the point at which the plunger clears the cylinder is designed as the preliminary stroke and the following high rate actuation of the ram piston is designed as the proper impact stroke. In order to maintain the plunger within the cylinder or maintain the plunger at its initial position, the ram piston is provided with an abut surface which is subjected to the pressure within the pressure chamber for prevention of actuation of the ram piston thereby to maintain the piston in the initial position.

Thus, according to the present invention, the ram is positively held in the initial position and when the ram is actuated, since the ram firstly moves along the preliminary stroke passage and thereafter initiates the proper impact stroke, there is no danger in the time of actuation and since the ram is actuated by the gas pressure in the proper impact stroke, a substantially high energy rate can be obtained, and since the gas pressure is sealed within the gas pressure chamber, there will be loss of gas pressure whereby a quite practical high energy rate forming machine can be provided.

Brief description of the drawing

The above and other objects and advantages of the invention will be more readily apparent from the following description when read in connection with the accompanying drawings in which:

FIG. 1 is a longitudinally cross-sectional view of a preferred embodiment according to the present invention; and

FIG. 2 is a longitudinal cross-sectional view of a modified embodiment according to the present invention.

Description of the preferred embodiments

In FIG. 1, the ram 2 to which an upper metal mould 1 is secured faces the top end surface of a bolster 4 to which a lower metal mould 3 is secured. The ram 2 is provided with a piston 5 which has a diameter of d_1 and is vertically movable along a pair of guides 7 and 7 supported

ported by the machine frame 6. A gas pressure chamber is provided on the frame 6 and the pressure chamber 8 is a diameter substantially larger than that of the piston.

The pressure chamber has gas under a high pressure aled therein. The ram piston 5 upwardly extends through e bottom wall 9 of the gas pressure chamber 8 into e interior of the chamber 8 and is provided at the upper end with a plunger 10 whose diameter is larger an the diameter d_1 of the piston 5 and is substantially naller than the diameter of the chamber 8. The diameter of the piston 10 is indicated by d_2 in FIGS. 1 and 2. The plunger 10 is so constructed that the plunger just s, in a cylinder 11 provided in the upper portion of the chamber 8 and having a diameter substantially the same that of the plunger 10. The bottom wall 9 of the pressure chamber 8 with which the ram piston 5 connects and the plunger 10 with which the cylinder 11 contacts are respectively provided with packings 12 and 13 for prevention of the high pressure gas from leaking it of the gas pressure chamber 8. The above gas pressure chamber 8 and cylinder 11 are connected to each other y means of a conduit 15 having a check valve 14 which pens only to the chamber 8 and a conduit 15' having a suitable switching valve 16. Vertical jack cylinders 17 are provided in the lower portion of the frame 6 and ave jack pistons 18 inserted therein respectively. The opposite ends of the jack cylinders 17 are communicated ith fluid pressure conduits 20 and 21 respectively and e conduits 20 and 21 are controlled by a change-over valve 19. The upper ends of the jack pistons 18 upwardly stend through the bolster 4 and face the ram 2.

FIG. 1 shows when the ram 2 is in the initial position and the ram piston 5 is pushed up to the upper dead point A and the plunger 10 is inserted deep into the cylinder 11. Accordingly, the gas pressure of the gas pressure chamber 8 imparts an upwardly directing force a the lower surface of the plunger 10 thereby to maintain the ram 2 in the initial position as shown in FIG. 1. Prior to the actuation of the ram 2, the jack pistons 18 are allowed to descend and then a work 22 is placed on ie top of the lower mould 3. Thereafter, the valve 16 is opened to allow the gas pressure within the pressure chamber 8 to flow through the conduit 15' to act on the cylinder 11 thereby to push the plunger 10 down. Since ie upper surface of plunger 10 is subjected to downward force at the area corresponding to the diameter d_1 of the piston 5, the plunger 10 descends down together ith the piston 5 and ram 2 along the preliminary stroke assage L which corresponds to the length of the plunger 0 and immediately after the upper surface of the plunger 0 has cleared the lower end B of the cylinder 11, the pressure of the pressure chamber 8 acts on the upper rface of the plunger 10, and accordingly, the ram piston descends down at a high rate together with the ram 2. In this stroke of the piston the work 22 is plastically formed to a desired shape by a cooperative action between ie upper and lower metal moulds 1 and 3.

In order to allow the descended ram 2 to rise again to the initial position, the change over valve 19 is shifted so as to introduce the fluid pressure below the jack cylinders 17 thereby to push the jack pistons 18 and accordingly, the ram 2 is pushed to the upper initial position again. Thereupon if the valve 16 is maintained closed, even if the plunger 10 enters into the cylinder 11, the as which has been trapped in the cylinder 11 pushes open e check valve 14 in the conduit 5 and flows back into ie gas pressure chamber 8, and accordingly, the ram piston 5 can rise easily. When the ram piston 5 again ssumes the position as shown in FIG. 1, the gas pressure within the gas pressure chamber 8 acts on the lower rface of the plunger 10 and thus maintains the ram 2 in the raised position up to the upper dead point A and the jack pistons 18 are again allowed to descend to the lower position and are held there.

In the modified embodiment of FIG. 2, the plunger 30

is disposed within the upper portion of the gas pressure chamber 28 and is downwardly directed, and the cylinder 31 is provided at the top end of the ram piston 25. When the ram piston 25 is pushed up to the upper dead point A, the piston 25 is held in this position by the gas pressure acting on the lower surface of the cylinder 31. The preliminary stroke passage L of the ram piston 25 is the distance covered by the cylinder until the upper end of the cylinder 31 moves away from the lower end of the plunger 30, and thereafter, the cylinder 31 is subjected to the pressure of the gas pressure chamber 28 and the ram piston 25 is actuated at a high rate thereby.

When the ram 2' is desired to be actuated, the jack pistons 38 may be employed instead of the pressure of the gas pressure chamber 8 being introduced into the cylinder 11 as in the embodiment of FIG. 1. The actuating mechanism is designed so as to the fulfill purpose, that is, the jack piston 38 of the jack cylinders 37 are provided with smaller diameter rods 36 and the rods 36 extend through the ram 32 and have heads 35 at their respective ends. When the jack pistons 38 are caused to descend, the heads 35 come to contact with the upper surface of the ram 32 and the ram 32 is pushed down by the downward movement of the jack pistons 38 and initiates the proper impact forming stroke. When the actuating mechanism as shown in FIG. 2 is employed, the switching valve 16 and conduits 15' which are necessary in the embodiment of FIG. 1 can be eliminated.

According to the present invention, the gas pressure within the gas pressure chamber can be adjusted. For example, if the gas pressure chamber 28 is filled with a certain amount of liquid and the liquid amount is adjusted by the manipulation of the valves 24, 26, and accordingly, the gas pressure within the gas pressure chamber can be varied. Any variation in the gas pressure may vary the downward movement rate of the ram piston, and accordingly, any desired high energy rate forming efficiency can be obtained.

While two embodiments of the invention have been shown and described in detail it will be understood that they are for the purpose of illustration only and are not to be taken as a definition of the scope of the invention, reference being had for this purpose to the appended claims.

What is claimed:

1. A high energy rate forming machine which comprises: a ram adapted to be actuated at a high rate by gas pressure; a piston provided on said ram; a pressure chamber adapted to contain gas under high pressure and having a diameter substantially larger than the diameter of said piston, said piston passing through a sliding seal in one end of said chamber; a plunger-cylinder assembly disposed between one end of said piston and the other end of said pressure chamber, said plunger being formed integral with said piston and said cylinder being formed integral with said piston and said cylinder being formed integral with said pressure chamber; and a jack device located entirely outside said chamber for returning said ram to its initial position after it has descended; said cylinder and said pressure chamber communicating with each other by means of a check valve which opens only to said gas pressure chamber, and said cylinder and said pressure chamber also communicating with each other by means of a switching valve.

2. A high energy rate forming machine as claimed in claim 1, in which a liquid supply device is further provided, said liquid supply device being adapted to supply any desired amount of liquid into said pressure chamber so as to vary the gas pressure within said chamber, the surface of said liquid within said chamber being in direct contact with said gas.

3. A high energy rate forming machine which comprises: a ram adapted to be actuated at a high rate by gas pressure; a piston provided on said ram; a pressure chamber adapted to contain gas under high pressure and having a diameter substantially larger than the diameter

of said piston, said piston passing through a sliding seal in one end of said chamber; a plunger-cylinder assembly disposed between one end of said piston and the other end of said pressure chamber, said plunger being formed integral with said piston and said cylinder formed integral with said pressure chamber; a jack device located entirely outside said chamber for returning said ram to its initial position after it has descended; said jack means actuating said piston by forcibly separating said plunger from said cylinder.

4. A high energy rate forming machine as claimed in claim 3 in which a liquid supply device is further provided, said liquid supply device being adapted to supply any desired amount of liquid into said pressure chamber so as to vary the gas pressure within said chamber, the surface of said liquid within said chamber being in direct contact with said gas.
